LUMBER SAW SHARPENER

Rudolph Heino, Mokomon, Ontario, Canada

Application January 7, 1936, Serial No. 57,995

3 Claims. (Cl. 76—31)

My invention relates generally to means for sharpening the teeth of circular lumber saws, and particularly to means of this character which is brought into action without dismantling or 5 stopping the saw and while the saw is rotating, whereby the saw may be sharpened as it is shifted back and forth into action, and an important object of the invention is to provide mechanically efficient and durable means of this character.

10 Another very important object of the invention is to provide sharpening means of the character indicated above which can be brought into action simply by the manipulation of a lever during the shift of the saw from the work.

15 Other important objects of my invention will be apparent from a reading of the following description in connection with the drawings, wherein for purposes of illustration I have shown a preferred embodiment of my invention.

20 In the drawings:—

Figure 1 is a general side elevational view of the embodiment.

Figure 2 is a longitudinal vertical sectional view taken through the file carrier and showing the same applied to the teeth of the lumber saw.

Figure 3 is a top plan view of the file carrier.

Figure 4 is a longitudinal vertical sectional view taken through one of the file assemblies.

30 Figure 5 is a transverse vertical sectional view taken through Figure 4 approximately on the line 5—5.

Figure 6 is a horizontal sectional view taken through Figure 4 showing the arrangement of one of the spring tighteners.

Figure 7 is a transverse vertical sectional view taken through the support arm and a portion of the file carrier showing the file carrier braking arrangement.

40 Figure 8 is a perspective view of one of the file blocks.

Referring in detail to the drawings, the numeral 5 refers generally to a suitable standard which is mounted by means generally indicated by the numeral 6 on a suitable support 7 adjacent the lumber saw, which standard has a rearwardly extending pivot bracket 8 to which is pivoted the lower end of a manual operating lever 9 which has a dog operating member 10 which is operatively connected by a rod 11 to the dog 12 which operates in connection with the notched segment 13 mounted above the bracket 8 on the standard 5.

The upper end of the standard 5 has journals 55 generally designated 14 which receive an axle

15 which is held in place by nuts 16, the axle having pivoted thereon the lower end of the file carrier support arm 17 which when in operative position is designed to rest against the stop 18 on the upper end of the standard, as clearly 5 shown in Figure 1. A point of the support arm 17 above the axle 15 is pivotally connected by one end of a lever 19 to an upper part of the lever 9 as indicated by the numerals 20 and 21, respectively, whereby swinging motion is applied to the support arm 17 by manipulation of 10 the lever 9. In the left hand position in which the support arm 17 is shown in Figure 1, the device of the invention is in the operative position, whereas when the lever 9 is swung rearwardly or toward the right, the support arm 17 15 will be holding the file carrier out of operative relation to the lumber saw.

The file carrier support arm 17 comprises the straight part 22 which has its upper end extended into a laterally and acutely angulated part 23 which has a general horizontal position illustrated in Figure 1 while in operative position. The left hand end of the portion 23 has a rearwardly angulated portion 24. There are two 25 of the portions 23, each having a part 24 (as shown in Figure 3) arranged on opposite sides of the file carrier which is generally designated 25.

The inner sides of the upper ends of the parts 30 24 (shown in Figure 7) are provided with concave rounded recesses 26 which receive the correspondingly shaped brake members 27 which have a flat side applied in braking relation to the outer sides of the file carrier side plates or disks 35 28.

Traversing the portions 24 and the brakes 27 is the threaded rod 29 which has its threaded ends extending beyond the portions 24 and equipped with nuts 30 which can be turned so as 40 to bear against the outer side of the members 24 and thereby force the brakes 27 with greater pressure against the outer sides of the file assembly disks 28, and thereby increase the resistance of the file carrier to being turned by the 45 saw, so as to increase the filing effect of the files on the teeth of the lumber saw.

The file carrier generally designated 25 includes the circular side disks or plates 28 which have center openings threaded as indicated by 50 the numeral 31 and receiving the threaded ends of the journal 32 which turns on the rod 29, and nuts 33 are provided on the threaded portions 31 of the member 32 to bear against the inner sides of the disks, whereby the disks are rigidly as- 55

sembled for rotation with the member 32 and with relation to the brakes 27.

At equal circumferentially spaced intervals the file carrier plates are traversed by axles 34 which have cotter pins 35 in the opposite ends thereof bearing against the outer sides of the said disks. Adjacent each axle 34 and fastened between the disks 28 are the spring holders 36 and 37 which have openings 42 therein in which one end of the respective springs 38 and 39 are tethered. Each spring holder (as shown in Figure 6) is provided at one end with a head 40 which bears against the outer side of one of the disks 28 and at its opposite end with a threaded portion equipped with a nut 41, the loosening of which will enable the rotation of the spring holder to wrap a portion of the spring concerned around the tightener or unwind the same therefrom, so as to tension or relax, respectively, the corresponding spring. The holder may be locked in the new position by simply tightening the nut 41.

Rockable on the axle 34 is the corresponding one of the file assemblies 43 which consists of a U-shaped body 44 having the acutely angulated bight portion 45 on which is a threaded boss 46 in which is threaded a tightening screw 47. The bight portion has L-shaped retaining flanges 48 under which the corresponding file 49 is placed in the manner indicated in Figure 5. The file is locked rigidly in place by tightening the screw 47 against the back of the file. Each file assembly is equipped also with a spring tightener rod 50, similar to the spring holders 36 and 37, and equipped with a spring end receiving opening 51. The axle 34 is rotatably received in openings 52 in the arms of the body remote from the bight portion. A spring and receiving opening 53 is provided in a portion of the bight as shown in Figure 4 for receiving one end of the spring 38, the spring 39 being engaged with the opening 51 of the tightener 50 in the case of each file assembly. The file assemblies are arranged relative to the file carrier and to the teeth 54 of the lumber saw 55 in the positions clearly shown in Figure 2, and circumferentially spaced so that as one tooth leaves a file assembly the next file assembly will be pulled into the original position of the first engaged file assembly, to act upon the succeeding tooth of the saw, whereby the rotation of the saw 55 applies the edges of the teeth 54 to the files 49. The file carrier 25 is rotatable in a counterclockwise direction as shown in Figures 1 and 2. The springs 38 and 39 are so arranged that the file assembly is yieldably held in a position to be engaged by a saw tooth as the device is applied to the saw for the sharpening of the teeth thereof. As the tooth of the saw engages the file 49, the springs permit the file to be moved by the tooth into a position parallel to and along the edge of the tooth. The engagement of the saw tooth with the file not only produces this displacement of the file assembly, but causes the tooth edge and the file to move in opposite directions while engaged, whereby the filing action is

accomplished and the tooth edge sharpened. As soon as the tooth has moved to a point in its clockwise rotation where it is about to leave the file assembly, the saw tooth pushes the file assembly over in a manner to cause additional displacement thereof and at the same time turn the file carrier in the counterclockwise direction to bring the succeeding file assembly into the path of the next succeeding tooth of the saw. It is to be noted that as soon as the tooth reaches a position in which it clears the file assembly engaged, the springs of the file assembly will return the file assembly to initial position. It is believed obvious that the files 48 are so angulated in their original or initial position of the file assemblies that the springs positioning the file assemblies are enabled to cause the face of the files to follow the contour of the saw tooth edges in a manner to effectively file and sharpen these edges, whereby the files are dragged along the cutting edges of the teeth and the sharpening thereof accomplished while the file assembly is in operative relation to the saw and while the saw is rotating. By means of the arrangements described the teeth of the lumber saw may be sharpened very quickly and accurately and efficiently.

Although I have shown and described herein a preferred embodiment of my invention, it is to be definitely understood that I do not desire to limit the application of the invention thereto, and any change or changes may be made in the materials, and in the structure and arrangement of the parts, within the spirit of the invention and the scope of the subjoined claims.

What is claimed is:—

1. A device for sharpening the teeth of a rotary lumber saw while said saw is rotating and comprising a standard, a pivoted support carried thereby, a carrier rotatably mounted on said pivoted support, saw sharpening elements pivotally mounted on the carrier and means cooperating with said elements for yieldably maintaining the same in position for contact by the teeth of the saw.

2. A device for sharpening the teeth of a rotary lumber saw while said saw is rotating and comprising a standard, a pivoted support carried thereby, a carrier rotatably mounted on said pivoted support, a file pivotally mounted on the carrier and means engaging the carrier for yieldably urging the file into sharpening relation with the edges of the teeth of the saw by the engagement of the teeth therewith while the saw is rotating.

3. A device for sharpening the teeth of a rotary lumber saw while said saw is rotating, said device comprising a standard, a pivoted support carried thereby, a file carrier rotatably journaled on the support, a plurality of file assemblies pivotally mounted by the carrier and spring means yieldably maintaining the assemblies in the path of the teeth of the saw for contact thereby during the rotation of the latter.

RUDOLPH HEINO.
